N. W. SNEERS.
Shutter Worker.

N° 8,597.

Patented Dec. 16, 1851.

UNITED STATES PATENT OFFICE.

NOAH W. SPEERS, OF CINCINNATI, OHIO.

BLIND AND SHUTTER OPERATOR.

Specification of Letters Patent No. 8,597, dated December 16, 1851.

To all whom it may concern:

Be it known that I, NOAH W. SPEERS, of Cincinnati, in the county of Hamilton and State of Ohio, have invented new and useful 5 Improvements in Window-Blind Operators and Fasteners; and I do hereby declare the following to be a full, clear, and exact description of the nature, construction, and operation thereof, reference being had to the 10 annexed drawings, making part of this specification.

The object of my invention is to provide a simple and secure method of operating and fastening outside window shutters and 15 blinds, without opening the windows, and I have invented the present in view of a number of contrivances, which appear to me to be lacking in strength when force is applied, such as high winds, &c.

20 The annexed drawing is a horizontal view of this apparatus.

My present contrivance consists of but few parts and these admit of any requisite degree of strength being given to them which 25 can scarcely be said to be the case in those operated by pinion and spur wheels, &c., where a large number of pieces are crowded into the space which takes the place of the usual hinge, and projects from the face of 30 the building.

The parts of my blind operator are as follows; (premising that it is inserted under the lower horizontal piece or sub-sill of the window frame, and works immediately above 35 and almost touching the main sill, upon which the frame rests). An iron plate (a) with a rising flange (b) (by which it is secured in position), is let into a mortise of its own shape, on the under side of the window frame, the lower face resting upon the 40 sill. Near the outer edge of this, a pivot (c) is provided, upon which a lever (d), oscillates and is at its farther extremity connected to the shutter or blind by the stud 45 (e), which works in a groove or grooved plate in the under edge of the said shutter or blind and at the inner extremity (f), is connected by a link (g) with the lever (h), which is pivoted (i) near the inner edge of 50 the plate.

(k) is a rod, which at one end is formed into a handle entering the room, and at the other end is bifurcated or forked, so as to straddle the lever (h), upon which it is 55 slidable, so that when drawn out, it possesses an increased leverage upon the shutter, and when retracted or pushed in, it need not project more into the room, than is sufficient for

the grasp, so as to be out of the way when out of use. Its capacity for elongation and 60 retraction, is also made to serve another purpose about to be explained.

Affixed at proper positions in the plate (a), are studs (j j') which project upward from its surface, and by the pressure or 65 bearing of the handle, or extension member (k) of the lever, against or between these when thrust inward, the whole affair is locked, and does not admit of motion of the shutter or tampering from the outside. 70

The permanent portion (h) of the lever, which is pivoted at (i) and linked at its outer end to the external lever (f d), is raised so much above the plate that it sweeps clear of the studs (j j') but the extension 75 portion or handle (k) avoids them only when protracted, which action as has been before stated gives also a greater leverage. The sides of the lever, which come in contact with the studs are tapered off in such 80 a manner, as to fall easily into, and wedge tightly up to the positions of shut, half open and fully open, the first named position being shown by red lines, (the lever being extended) and the left side, (it being for a 85 right hand shutter) coming in contact with the stud. In the second position of half open, the extension lever is thrust between the studs (j) and (j'). In the black lines, the apparatus being shown wide open, the 90 left side of the lever is in contact with the stud.

Having thus fully described the nature of my improvements in window blind operators and fasteners what I claim therein as new 95 and desire to secure by Letters Patent is—

The combination of the extension handle (k) (provided with taper ends) with the lever (h), and the studs (j j'), or their equivalents, by which the handle can by extension, be made to possess the requisite leverage, and by which when the lever arrives at that portion of its sweep, corresponding to the required position of the blind or shutter, it is firmly secured in its position, and the 100 handle placed out of the way by the latter being thrust home against the studs, the 105 whole being arranged substantially in the manner described.

In testimony whereof, I have hereunto set 110 my hand before two subscribing witnesses.

N. W. SPEERS.

Witnesses:

JOHN R. WRIGHT,
EDWARD H. KNIGHT.
